TOOTHBRUSH

Filed July 29, 1930

Inventor:
Leo Levy
By His Attorney:
Otto Munk

UNITED STATES PATENT OFFICE

LEO LEVY, OF KAISERSLAUTERN, GERMANY

TOOTHBUSH

Application filed July 29, 1930, Serial No. 471,469, and in Germany August 26, 1929.

In tooth-brushes made of a material liable to be molded when submitted to heat, such as celluloid or similar natural or artificial products of that type the bundles of bristles are usually stamped or anchored in the material of the head of the brush. However this method of attaching the bristles is objectionable in that the head of the brush upon its heating in hot water for cleaning purposes will yield and the anchoring be opened, whereby the bristles will be detached and the anchoring opened more and more with the result that the brush will be soon useless. Moreover the detaching of the bristles during the use of the brush may easily produce accidents prejudicial to the health of the user.

Therefore attempts have been made for avoiding these objections by housing and tightening each bundle of bristles in a metal sleeve glued, cemented, screwed or otherwise suitably secured in the material of the head of the brush. In this way the bristle retaining anchor is housed within a metal part which is less subject to distortions by the action of heat. This method of attaching the bundles has the advantage that the bristles cannot be easily detached, but it is objectionable in that the metal sleeves cannot be securely attached in the body of the brush.

A further objection is that the sleeves require much space so that a small number of bundles only can be mounted in a space corresponding to the head surface of a usual tooth-brush. Therefore the heads of the brushes must be limited to certain shapes as well as the arrangements of the bristles. Moreover the cementing or screwing of each individual sleeve as well as the securing of each individual bundle in the corresponding sleeve require much time and increase the cost of manufacturing. Heretofore it was not yet possible to prevent the metal sleeve parts from projecting from the brush heads, whereby such parts will be subject to alterations by their contact with saliva and dentifrice.

All these objections will be avoided by my present invention owing to the fact that one or more metal plates are embedded in any

known way in the moldable material of the head of the brush, said plates serving to attach the various bundles of bristles, whereby the attaching means of the bristles may be inserted simultaneously in the plate or plates and the material of the brush itself. The location of the bundles and attaching means thereof may thus be effected by the usual automatic machines used in the manufacture of brushes, whereby the manufacture will be simplified and a great deal of work saved.

In the accompanying drawings I have illustrated by way of example three preferred embodiments of my invention. In these drawings:

Fig. 1 is a side elevation of the tooth-brush.

Fig. 2 is a top plan view thereof.

Fig. 3 is an enlarged fragmentary longitudinal section of Fig. 1.

Fig. 4 shows a tooth-brush having a reinforced handle.

Fig. 5 shows a tooth-brush with a plurality of metal plates for attaching the bristles.

Completely embedded in the head of the brush *a*, made of celluloid or other plastic material is a plate *c* of soft metal. Said plate is solid and the bundles of bristles are inserted into the same with their attaching means by the usual automatic machine after the plate has been secured in the material of the head *a*.

In the finished brush, that is after the insertion and securing of the bundles of bristles in the plate *c* and head *a* said plate will therefore have holes *d* corresponding to the various bundles of bristles. Each hole *d* in the plate *c* corresponds to a hole *e* in the head *a* on the side turned towards the bristles. The metal anchors *f* inserted into the holes *d* and *e* are firmly stamped in said holes, whereby said anchors will be held in the metal plate as well as in the head *a* of the brush.

The metal anchors *f* may also be shaped in such a way that they will be arranged not only above the plate *c* but also below said plate.

The shape of the plate *c* corresponds to the shape of the brush in such a way that said plate will be surrounded on all sides by the material of the head of the brush (Fig. 2). 100

As shown in Fig. 4 the metal plate *c* may serve to reinforce the handle *b* of the brush, said plate being extended through said handle.

5 In the embodiment illustrated in Fig. 5 I have provided two metal plates *c*¹ and *c*². As already described, the brush may be manufactured in the usual machines after the insertion of the metal plate or plates into the head of the brush or into the latter and the handle thereof respectively, whilst for the usual brushes with sleeves or sockets for the reception of the bundles of bristles particular devices and complicated manipulations 10 were required.

15 Having now fully described my said invention, what I claim and desire to secure by Letters Patent, is:

1. A tooth-brush comprising a metal plate 20 completely embedded in the material forming the head of the brush, and tufts of bristles inserted through one side of the head and anchored in the said metal plate.

2. A tooth-brush comprising a strip of 25 soft metal, completely embedded in the material forming the brush, and extending in the head and handle thereof, and tufts of bristles inserted through one side of the head and anchored into the portion of said strip 30 of soft metal extending through the head.

3. A tooth-brush made of a moldable material and comprising a plate of soft metal embedded in the head of the brush, and ferruled tufts of bristles provided with a metal 35 anchor inserted through one side of the head, and anchored into said soft metal plate and into the material forming said head.

Dr. LEO LEVY.
